UNITED STATES PATENT OFFICE.

HUGO PICK, OF CHICAGO, ILLINOIS.

DESIGN FOR A TUMBLER.

47,798.

Specification for Design. Patented Sept. 7, 1915.

Application filed June 7, 1915. Serial No. 32,745. Term of patent 14 years.

To all whom it may concern:

Be it known that I, HUGO PICK, a citizen of the United States, residing at Chicago, in the county of Cook and State of Illinois, have invented a new, original, and ornamental Design for Tumblers, of which the following is a specification, reference being had to the accompanying drawing, forming a part thereof.

In the drawings: Figure 1 is a side elevation of a tumbler embodying the invention and Fig. 2 is a plan.

Copies of this patent may be obtained for five cents each, by addressing the "Commissioner of Patents, Washington, D. C."

The invention is characterized in having its lower portion formed of a slightly outwardly flaring side *a*, a shallow, but apparently abrupt bend *b* and an upper portion *c*, tapering inwardly from the portion *b*.

I claim:

The new and ornamental design for a tumbler as shown and described.

HUGO PICK.
